UNITED STATES PATENT OFFICE.

ALLEN D. CARDWELL, OF BROOKLYN, NEW YORK.

ELECTRICALLY-OPERATING TRANSLATOR.

1,290,079.

Specification of Letters Patent.

Patented Jan. 7, 1919.

Application filed December 1, 1915. Serial No. 44,427.

To all whom it may concern:

Be it known that I, ALLEN D. CARDWELL, a citizen of the United States, and a resident of New York city, borough of Brooklyn, county of Kings, and State of New York, have invented certain new and useful Improvements in Electrically-Operating Translators, of which the following is a description.

10 My invention has reference to improved means for selecting and setting in operative position any desired number of members or parts, in a desired succession or sequence, whereby various operations or functions of 15 certain electrically controlled apparatus may be effected.

My improvements are particularly adapted for use as translators at transmitting or receiving stations, or both, in telegraph type- 20 writer systems, and may be utilized in such systems to cause the selection and operation of various elements for printing or type-writing and other working functions of a printing or typewriting machine.

25 In my application for Letters Patent for improvements in electric controlling systems, filed Sept. 5, 1914, Serial No. 860,318, I have set forth a system whereby, by means of two translators located at different stations and rotating isochronally, a signal sent from one of the stations, in the form of a group of impulses, may selectively control a series of relays under the immediate control of the translator at the other station. Said

30 application discloses means whereby a starting impulse is sent from the transmitting station, prior to the transmission of each signal, for starting the operation of the receiving translator, and other means for stop-

35 ping the translator at the completion of each signal. The receiving translator is illustrated as being adapted to successively operate contacts contained in a series of circuits, to thus place said circuits under the

40 control of a line relay, which is energized upon the reception of each impulse. In this way, the circuits are selectively operated in accordance with the character of the signals received. These circuits control relays 45 which in turn control the operations of the recording device, and thus effect the recording of the signals transmitted.

In my application for Letters Patent for improvements in telegraph typewriters, filed 50 April 10, 1915, Serial No. 20,386, I have set forth a telegraph printer having a type

wheel or member adapted to be rotated and moved longitudinally to bring its type to a printing position, together with a hammer for effecting printing from such type, and 60 devices to cause various operations of a paper carriage and other functions of the machine. In said application I have illustrated also an electrical system adapted to control the various magnets of such printer, 65 in conjunction with a line relay and controlling relays through which circuits are controlled by a translator by signals sent from a keyboard at a transmitting station, substantially in accordance with my invention 70 set forth in my aforesaid application Serial No. 860,318.

My present invention has to do with distributors or translators which are of general application to electrical systems for the 75 transmission of intelligence, and to recording or printing devices adapted for use in connection with such systems. However, in order that a more complete understanding may be had of my present improvements, I 80 have illustrated them herein as applied to a system and a recording device similar to those described in my aforesaid applications. It is to be understood, however, that this particular embodiment of my invention is 85 intended merely as an illustration of one of the many uses to which it may be put.

My improved translator or distributor embodies a series of movable elements and controlling means therefor, the controlling 90 means being in turn controlled by the signals received. The movable elements may serve any desired purpose. For example, they may operate contacts for controlling printing magnets, such as are shown in my 95 application Serial No. 20,386, to position a type wheel, or they may be used to operate mechanical means for selecting independent type carrying members, such as type bars.

The controlling means above referred to 100 include, as herein illustrated, a controlling member corresponding to each of the movable elements and means for effecting the successive operation of these members during the reception of each signal, irrespective 105 of its character. In addition, the controlling means include a device which is operated only upon receipt of an active impulse, by which term I mean an impulse of a given characteristic, such, for example, as a long 110 impulse as distinguished from a short one, a positive impulse as distinguished from a

negative one, or, in systems operating with impulses of constant duration and direction, an impulse as distinguished from no impulse. For the sake of clearness and brevity, I will describe my present invention as used in connection with a system of the latter type.

The above mentioned controlling members are so arranged that the movement of 10 one of them will cause the operation of its corresponding movable element only in case the impulse-controlled device is operated at the time at which the movement of the member occurs. In other words, the conjoint 15 action of the impulse-controlled device and the controlling member corresponding to a given movable element, is required in order that that element may be caused to operate. Thus, since the controlling members operate 20 in regular succession during the reception of a signal, irrespective of the character of the signal, and since the impulse-controlled device operates only upon the reception of an impulse, the particular movable element or elements operated by a given signal are determined by the timed relation 25 of the impulses comprising that signal.

In addition to the above described parts, I provide means for restoring all of the 30 movable elements to normal position upon the completion of each signal.

My invention further comprises novel 35 details of improvement and combinations of parts that will be more fully hereinafter set forth and then pointed out in the claims.

Reference is to be had to the accompanying drawings forming part hereof, wherein,

Figure 1 is a side elevation, partly in section, of a translator embodying my invention;

Fig. 2 is a plan view thereof;

Fig. 3 is an enlarged detail of the cam shaft;

Fig. 4 is a cross section of Fig. 3;

Fig. 5 is an enlarged vertical longitudinal section of Fig. 3 of the machine;

Fig. 6 is a cross section substantially on the line 6, 6, in Fig. 5;

Fig. 7 is a cross section substantially on the line 6, 6, in Fig. 5, looking to the right hand side thereof;

Fig. 8 is a fragmentary section of parts shown in Fig. 5, showing the parts in a different position;

Fig. 9 is a detail view of parts shown in Fig. 8 in a different position;

Fig. 10 is a sectional detail illustrating the cam shaft operating means;

Fig. 11 is a sectional detail of a modification; and

Fig. 12 is a diagrammatic view of a circuit system embodying my improvements.

Similar numerals and letters of reference indicate corresponding parts in the several views.

In the accompanying drawings, the numeral 1 indicates a suitable frame or casting, in which a plurality of movable elements or members 2 are pivotally supported, as upon a rod 3. The members 2 are normally retained in a definite position and are adapted to be moved or to move from such position separately. I have shown the members 2 retained in normal position by latches or bell-cranks 4, one for each member, which are pivotally supported upon a rod 5, suitably carried by frame 1.

In the example illustrated, the upper ends of the latches 4 normally engage stops or notches 2^a of members 2, as illustrated in Fig. 5, the projections 2^b adjacent to said stops normally limiting the rearward motion of said latches under the influence of springs 6 coacting with said latches. Springs 6 may be suitably supported in the frame, as upon a cross bar 7. When the latches are moved from the stops 2^a, as illustrated in Fig. 9, the members 2 are adapted to drop to rest upon corresponding latches aided by springs 2^c. To cause the latches 4 to be operated to release the corresponding members 2, I have shown controlling members or arms 8 pivotally supported in frame 1, as at 9, said arms being provided with pawls 10 shown pivotally supported upon said arms at 11, and normally under the influence of springs 12 connecting said pawls with said arms, the tendency of said pawls being to move under the latches 4. Said pawls are normally held in check against the tension of springs 12 by means of a bar 13, adapted to be moved to permit said pawls to pass under the corresponding latch 4 (Fig. 9) and to restore said pawls to their normal positions (Fig. 10). The parts 2, 4, 6, 8 and 14 may be carried on a sub-frame 7.

In order to reciprocate the pawls 10 to cause operation of latches 4, I have shown a shaft 21 supported in suitable bearings 110 in frame 1 and having cams 21^a, 21^b, 21^c, 21^d and 21^e, adapted to operate the respective arms 8, in relation to which said cams are set. I have illustrated the arms 8 as provided with cam followers or projections 8^a, 115 adapted to coact with said cams to operate said arms. In the example illustrated, there are pairs of opposing cams for each arm 8, and five such pairs of cams to coact with five such arms. It will be understood, however, 120 that there may be any desired number of arms 8, and one or more cams for each arm, according to the number of steps shaft 21 is to be rotated for a complete signal. Screws 14 carried by sub-frame 7 and coacting with arms 8 are adapted to limit the downward movement of arms 8, and to adjust the time of contact of the cam followers or projections 8^a with the corresponding cams.

The cams 21^a, 21^b, etc., are arranged as shown to successively coöperate with the cam followers 8^a on the several arms 8, so that the rotation of the shaft 21 will effect the successive upward movement of the several arms 8. It is apparent that if the bar 13 is withdrawn to allow the pawls 10 to be swung by the springs 12 into position underneath the latches 4, at the time when any arm 8 is elevated by its cam, the corresponding latch 4 will be swung about its pivot and will permit the corresponding member 2 to drop down into the position shown in Fig. 9. Since the arms 8 are all successively operated during the reception of each signal, the particular member or members 2 to be operated will be determined by the particular time or times at which the bar 13 is withdrawn. Thus, for example, if the bar 13 is withdrawn at the times when the first and fourth members 8 are being elevated, the first and fourth members 2 will be allowed to drop. By providing means for withdrawing bar 13 at the reception of each impulse, the timing of the impulses in a given signal will determine which of members 2 will operate upon the reception of that signal.

I have illustrated bar 13 as controlled by the armature A' of a magnet A, shown carried by frame 1, whereby when magnet A is energized bar 13 will be moved to one side to permit pawls 10 to pass under the latches 4, and when magnet A is deenergized, all of the five pawls 10 will be pushed back by such bar to their normal positions shown in Fig. 5. Spring a connected with the frame and suitably connected with bar 13 or armature A', serves to cause bar 13 to retain pawls 10 in normal position. The energization of magnet A will occur in accordance with the character of the signal on the line, as hereinafter set forth.

After a complete signal has been sent on the line to the translator, the members 2 that may have been operated, as well as the corresponding latches 4, for such signal, may be restored to normal in any suitable manner. For this purpose I have illustrated a restoring bar 15 shown beneath the free ends of members 2, and pivotally supported at 16 from the frame, which bar 15 is operatively connected with the armature L' of a magnet L carried by frame 1. A spring connecting restoring bar 15 of the armature L' with the yoke of magnet L serves to normally retain said bar retracted from members 2, and an adjustable stop c coacting with the arm carrying bar 15 of armature L' (Fig. 5) acts as a back stop for the armature and enables desired adjustment of the armature and bar 15 relative to the magnet L and members 2, respectively. Magnet L is adapted to be energized at the completion of each signal or group of impulses comprising a signal for restoring

the parts to normal, and in the example illustrated the sixth member 2^x is utilized for such purpose. As shown in Fig. 6, the bar 13 does not coöperate with the pawl 10^a mounted on the fifth arm 8, and, therefore, this pawl 10^a will operate its latch 4 each time it is elevated by its cam, irrespective of the position of the bar 13. As herein shown, the fifth arm 8 elevates pawl 10^a, as well as the fifth pawl 10 controlled by bar 13, since the latter pawl 10 and pawl 10^a are carried by the same arm 8.

From the foregoing it will be understood that the desired members 2 may be operated in succession, in accordance with the operation of the corresponding latches 4, as controlled by the signals on the line, and that the operation of the members 2 may be utilized to effect the operation of other desired devices. In the example illustrated in Figs. 1 to 10, and Fig. 12, I have shown contacts to be controlled by the members 2, for in turn controlling circuits to effect operation of some suitable recording device. In this particular embodiment of my invention, it is assumed that my present improvements are utilized to control magnets in a printing telegraph system, such as that set forth in my aforesaid applications, Serial Nos. 860,318 and 20,386. It will be understood, however, that the members 2, instead of being utilized to directly control electric circuits, may be utilized for any desired purpose, such, for example, as to control mechanically operated selecting devices, or selecting devices operated by the combination of mechanical and electrical means. Fig. 11, which will be referred to hereinafter, illustrates one method of utilizing members 2 for a purpose other than the closing of electrical contacts.

In Figs. 1, 2, 5, 6, 7 and 8, the arms 2 are illustrated as controlling contacts, 1^c, 2^c, 3^c, 4^c, 5^c, and E', respectively. The first five of these contacts may be arranged to control the circuits of magnets 1^d, 2^d, 2^d', 3^d, 3^d', 4^d and 5^d, similar to the type-wheel positioning magnets of my aforesaid applications, and the sixth contact E', which is preferably operated at the completion of each signal, may be arranged to control magnets for effecting the operation of the printing device, and for restoring the various parts of the translator or distributor to normal position.

The upper spring members of the contacts 1^c, 2^c, 3^c, 4^c, 5^c and E' tend to move downwardly, to close the contacts, but are restrained from so moving by the insulators x mounted on the members 2, when the latter are in normal position. When a member 2 is allowed to drop, however, the corresponding contact will close.

In addition to the individual contacts under the control of their respective members 2, it may be found desirable to provide

other contacts for selecting operating magnets to be actuated upon the closing of the contact E' at the completion of the signal. Such magnets may serve to effect the special operations of the printing device, such, for instance, as printing, word and line spacing, etc. When these latter contacts are employed, any suitable controlling means therefor may be provided. I preferably, however, 10 arrange these latter contacts so that they are controlled by the same members 2 which control the individual contacts above referred to. For example, I may so arrange these latter contacts that one or more of 15 them are operated upon the combined operation of certain of the members 2, that others are operated upon the operation of any of the members 2, and that still others are operated upon the operation of certain of members 20 2, acting individually. Thus, the set of contacts G' , G^2 is operated when all of the first three members 2 drop, the set of contacts H' , H^2 is operated when any one of the five members 2 drops, the set of contacts 25 i' , i^2 , i^3 and i^4 is operated upon the dropping of the fourth member 2, and the set of contacts j' , j^2 is operated upon the dropping of the fifth member 2. These sets of contacts 30 may be arranged to control the operation of a particular magnet in a group of magnets, such as O, P, N, M, R, Q, T, S, Fig. 12.

As a means for controlling contacts G' and G^2 , I have shown a bail or analogous movable arm G overlying members 2 and 35 pivotally supported at g upon sub-frame 7, adapted to control normally closed contacts G' and normally open contacts G^2 , said bail G being shown provided with a projection g' having insulation g^2 adapted to coact 40 with the lower spring g^3 (Figs. 1 and 6) to normally keep contact G' closed, which in turn keeps contact G^2 open by raising spring g^4 . An intermediate spring g^5 rests upon insulation g^6 . In the example illustrated 45 bail G is normally held up by the first, second and third members 2 (Fig. 6) and is only allowed to drop when said three members are operated in succession, because if any one of said three members 2 is not operated 50 on a signal, the bail G cannot drop, as it will be held up by such non-operated member. Said bail G is shown provided with a cut-away portion G^4 above the last three members 2, 2^x , permitting the bail to 55 drop or swing down when released by the first three operating together, (Fig. 6). A stop bar g^7 (Fig. 5) carried by sub-frame 7 beneath bail G serves to limit the downward movement of said bail when released 60 by the first three members 2. When bail G is raised upon the restoration of members 2 to their normal positions by bar 15, circuit will be broken at G^2 and closed at G' .

The contacts indicated at H' , H^2 are controlled by a second bail H located beneath

members 2 and adapted to be pushed down by any one of the first five of said members, but not by the sixth member 2^x . The bail H is shown pivotally supported in the sub-frame 7 at h and at its outer end is provided 70 with a projection h' having insulation h^2 adapted to be engaged and normally held up by the spring h^3 that carries one member of the normally open contacts H^2 , the other member of said contact being shown carried 75 by a spring h^4 . A spring h^5 carries the other member of normally closed contact H' , and said spring h^5 normally bears against insulation h^6 . As illustrated in Fig. 1, the springs of the contacts G' , G^2 , H' , H^2 are 80 carried upon the side of frame 1, and insulated therefrom and from each other, and the projections g' , h' operate in apertures e in the side of frame 1 (Fig. 1). The bail H is provided with a cut-out part at H^4 beneath the sixth member 2^x (Fig. 6), so that the bail H will not be affected by the dropping of the member 2^x , which occurs at the conclusion of each signal.

Contacts i' , i^2 , i^3 , i^4 are shown carried on 90 springs supported by and insulated from the frame and from each other. The spring i^5 rests upon insulation d and the springs i^6 , i^7 are normally held elevated by the insulation i^8 mounted on the spring carrying the upper member of contact 4^c . From Fig. 7 it is apparent that when the member 2 corresponding to contact 4^c is allowed to drop, contact 4^c will close, and two contacts i' , i^2 will be permitted to open, and the contacts i^3 , i^4 will close. The two springs i^6 are controlled simultaneously by the bridge member i^9 shown carried by upper spring of contact 4^c and in turn carrying the insulation i^8 , (Figs. 5 and 7).

The fifth member 2 which controls the normally open contact 5^c also controls normally closed contact j' and normally open contact j^2 thereabove, in the manner described with respect to contacts i' , i^3 . The contacts j' , j^2 110 are carried by springs normally insulated from frame 1, insulation j^4 on the top spring of contact 5^c coacting with the spring j^5 of contact j' . Contacts j^2 carried by two springs, the lower of which rests on insulation d , may be arranged similarly to that shown in Figs. 5 and 7, the arrangement being such that when the fifth member 2 drops, circuit will be closed at j^c , and circuit will be 120 closed at j^2 .

While in the foregoing description I have referred to members 2 as being adapted to selectively control electrical circuits, it will be understood that such members may control means for producing mechanical operations, either alone or in conjunction with electrically operating means. In Fig. 11 the member 2 is shown adapted to operate a rod or other element X , which in turn may cause 130

operation of any other suitable lever or part indicated at Y, whereby any desired operations of a printing or typewriting machine or other apparatus may be controlled in accordance with the operation of members 2. I have shown the rod or the like X provided with a stop X' adapted to be engaged by the extension 2^c of member 2 to operate the rod X when member 2 drops, as released by the latch 4. It will be understood that any desired number of members 2 and corresponding controlling devices may be utilized according to the result to be accomplished.

In order to render my improved translator effective, it is necessary to provide some means for rotating the shaft 21 at the receiving station, and preferably this rotation is isochronous with the rotation of a somewhat similar shaft located at the sending station. Any suitable means may be provided for effecting this rotation, which means may be operated continuously, or may be started prior to the sending of each signal and stopped at the completion of each signal. While the particular means employed for this purpose form no part of my present invention, I have herein illustrated the shaft 21 as being operated step by step during the reception of each signal by means similar to those disclosed in my aforesaid applications, which means I will now describe, the reference numerals used herein being for the most part the same as those applied to corresponding elements of said applications.

An electric magnet 22 is suitably supported upon frame 1, and to the armature 22^a of such magnet is connected a rock arm or lever 23, shown carrying two pawls 24, 40 25 (Fig. 10) arranged in reverse relation with respect to toothed wheel 26 secured upon shaft 21. A spring 27 connected with said pawls tends to keep them in contact with said toothed wheel. An adjustable 45 stop 28, shown adapted to coact with pawl 25 to limit its upward movement, causes the cam shaft to stop at the proper point after being advanced each step by said pawl, and a stop 29 is adapted to be engaged by pawl 50 24 to prevent overthrow of the shaft when operated by said pawl. A spring 30, connecting the arm 23 with the main frame, serves with magnet 22 to rock the arm or lever.

Magnet 22 is in a local circuit, including 55 normally closed contacts 32, shown carried by springs 33, 34 (Figs. 1 and 12), supported upon suitable insulation on the frame. The arm or lever 23 carries a stud 60 35, which is shown projecting through a hole 36 in frame 1, the stud on the first depression of arm or lever 23 depressing a contact lever or arm 37, suitably supported upon the frame as at 38, and carrying insulation 39, adapted to operate upon spring

34 to break the circuit at contact 32 as shown in Fig. 1, to open the local circuit of the translator magnet 22. Contact lever 37 is retained in its downward position by a latch pawl 40 that is pivotally supported 70 as at 41 upon an adjustable plate or arm 41^a that is pivoted as at 41^b upon frame 1, and adapted to be adjusted angularly around said pivot to vary the time of engagement of stud 35 with latch 40. Said 75 plate or arm 41^a is shown provided with a slot receiving a screw 41^c in frame 1 to retain said plate or arm in set position.

Latch 40 is normally controlled by a spring 40^b, and said latch has a stop portion 40^a adapted to engage the projecting portion 37^a of contact lever 37 to retain the local circuit of the magnet broken until the armature and its arm 23 have been restored nearly to normal, and thereupon the stud 35^a 85 80 arm 23 engages the projecting arm of latch 40 to release arm 37 to permit contacts 32 to again close each time magnet 22 is deenergized.

The cam shaft 21 carries, preferably at 90 one extremity thereof, a unison cam 31, the purpose of which is to insure a complete cycle of operation of one set of cams of the cam shaft for a given signal on the line. In the example illustrated, since there are two 95 cams for each arm 8, I provide the unison cam 31 with two opposing projections corresponding to each one-half rotation of the cam shaft, and the cam shaft is given one-half rotation for each series of five cams, 100 because the cams are arranged in pairs. If a single series of cams were arranged on the cam shaft, as illustrated in my said application Serial No. 860,316, the cam shaft would be given one complete rotation for 105 a given signal on the line, and if more than two cams were provided for each arm 8 the cam shaft would be given a corresponding partial rotation.

The unison cam 31, in the example shown, 110 being provided with opposing teeth 31^a, is adapted, in the normal position of rest (Fig. 1), to engage a tooth 45 on a spring 46 carried by and insulated from the frame and in electrical connection with spring 34, 115 whereby upon the first forward movement of shaft 21, resulting from the actuation of the line relay 51 by the initial starting impulse received over the line 50, a tooth 31^a passes from tooth 45 and permits contact 120 47 on spring 46 to engage a contact 48 that is connected with one winding of relay 49 (Fig. 12). Thus the working circuit of magnet 22 is closed at the beginning of an 125 operation, and is maintained closed at 48 until practically the completion of each one-half rotation of shaft 21, irrespective of the breaking of the circuit at 32 when shaft 21 commences to rotate for each signal or 130 group of impulses received.

Assuming that a combination or group of a starting signal and five selective signals in desired combinations are sent on the line for effecting a complete cycle of operations for 5 selecting and printing a character or for other functions of a telegraph typewriter or printer, the first or starting signal sent on the line will cause operation of relay 51 whose armature is connected to one side of 10 battery 58, and a circuit will be established from said battery through contact 54, resistance 59, armature 49^a of relay 49, back contact 56 of said relay to normally closed contact 32, thence through magnet 22 to ground and return to battery, and also 15 through variable inductance 60 and capacity 60^a in multiple with magnet 22 to ground (Fig. 12). Variable inductance 60 and capacity 60^a are provided for the purpose of 20 controlling the speed of operation of magnet 22, as described in my aforesaid application, Serial No. 872,320. Current will also flow from back contact 56 of relay 49 through a resistance 63 to ground.

25 Magnet 22 will now operate to first cause cam shaft 21 to rotate one step, whereupon unison cam 31 will release tooth 45 and permit contacts 47 and 48 to close, as above described. A circuit will then be established 30 from battery 58, through left hand winding of relay 49, through closed contacts 48, 47, through spring 34, contacts 32 and magnet 22 to ground, and through variable inductance 60 and capacity 60^a, whenever contact 35 32 is closed thereafter by the action of magnet 22, as previously explained. The operation of relay 49 causes the starting circuit of magnet 22 to be broken at contact 56, and thereafter each time the relay 51 is 40 operated by a line impulse a circuit will be established from the battery 58 through the armature of line relay 51, through resistance 59, armature 49^a, front contact 62 of relay 49, through a holding winding of said relay, 45 and through magnet A to ground, to effect the energization of said magnet.

It will be understood that operation of magnet A can take place only after a starting signal on the line has caused a partial 50 rotation of cam shaft 21. Thereafter, as cam shaft 21 is stepped successively, the arms 8 will be raised in succession and their pawls 10 will be reciprocated out of contact with their corresponding latches 4, except 55 when a line impulse effects the energization of magnet A, as before described, and the consequent withdrawal of the bar 13 from the pawls. Whichever pawl 10 is elevated while the bar 13 is thus withdrawn, will rock 60 its associate latch 4 to release the corresponding member 2 to permit said member to drop, as illustrated in Fig. 9. Upon the cessation of the impulse on the line, relay 51 is deenergized, the circuit of magnet A is 65 broken, and bar 13 is moved back to restore

all of the pawls 10 to normal position. The operated pawls and latches will then assume the positions shown in Fig. 8.

Relay 49 is designed to prevent a repeated operation of magnet 22 after a complete 70 cycle of operations of such magnet for a given signal has been performed, and, as shown herein, it operates also to connect magnet A to the circuit controlled by line relay 51 after each starting impulse has been 75 received. Relay 49 removes the starting circuit and magnet 22 from the control of the line relay 51 upon the establishment of a working circuit through contact 48. This circuit retains relay 49 operated as long as 80 contact 48 is closed, because of current flowing through magnet 22 and resistance 63. Whenever line relay 51 operates to energize magnet A it also energizes a holding winding of relay 49, so that if a circuit should 85 be retained closed by reason of the continuous energization of relay 51 until after magnet 22 has completed a cycle of operations, magnet 22 will not again be energized because relay 49 will remain operated by 90 reason of its holding winding being energized, as long as relay 51 is energized. At the end of a cycle of operations of magnet 22, unison cam 31 opens the circuit of magnet 22 at contact 48, and the cam shaft comes 95 to rest. The opening of this circuit restores relay 49 to normal, provided line relay 51 has returned to normal.

As above stated, the contact E' is closed at the completion of each signal, as for example by the fifth cam on shaft 21. This contact may control the circuit of a number of operating or special function magnets, such, for example, as those illustrated at M, N, O, P, Q, R, S, T in Fig. 12. Contact 105 E' also controls a circuit through the restoring magnet L which operates member 15 to restore the members 2 to normal position after the reception of each signal, but the magnet L is so timed that its operation will 110 be delayed until after the operation of the selected special function magnet or magnets.

Bearing in mind the fact that the contacts 1^c, 2^c, 3^c, 4^c and 5^c, which are operated by the corresponding members 2, control magnets 1^d, 2^d, 2^d''', 3^d, 3^d''', 4^d and 5^d, which serve, for example, to position a type wheel, and that the contacts G', G², H', H², i', i², i³, i⁴, and j', j², which are also operated by members 2, serve to include in the circuit 120 controlled by contact E' selected magnets of the series M, N, O, P, Q, R, S, T, for operating the telegraph typewriter or printer, the operation of my present improvements should be readily understood from the following examples:

Assume first that the signal received comprises an active impulse at the first time period and one at the third time period, but none at the second, fourth or fifth periods. 130

The result will be that the first and third members 2 will drop, operating contacts 1^c and 3^c, and therefore energizing magnets 1^a, 3^a and 3^a', to position a certain letter of the 5 type wheel in operative relation to the printing hammer. The dropping of these members 2 will also close contact H², and open contact H¹, it being remembered that this occurs when any one of the members 2 drops. 10 This operation of contacts H¹ and H² includes magnets T, Q and R in the circuit of contact E'. Then, upon the dropping of the member 2^c at the completion of the signal, contact E' is closed, which results first in the 15 energization of magnets T, Q and R, to effect the operation of the printing hammer, and such other operations as are necessarily incident to the printing of a character, and second in the energization of magnet L to 20 restore the parts to normal position.

Assume now that the signal received includes impulses at the first, second, third and fifth time periods, with no impulse at the fourth period. The first, second, third and 25 fifth members will drop successively, operating the contacts 1^c, 2^c, 3^c and 5^c. Also, since all of the first three members 2 have dropped, contact G² will be closed and contact G¹ will be opened, and since the fifth member 2 has 30 dropped, contact j' will be opened and contact j² closed. This results in including the magnet P in the circuit of contact E', and upon the dropping of the member 2^c to close this contact, this magnet alone will first be 35 operated to effect the desired operation of the printing device, and then the restoring magnet L will be operated.

As above stated, I have described my invention herein as applied to the system and 40 printing device of my former applications, merely as an example of one of the many uses to which it may be put. It should be understood, therefore, that my invention is not limited to any particular application 45 thereof, nor to the particular embodiment herein illustrated, since it is obvious that many changes may be made therein without departing from the spirit of my invention.

What I claim is:

50 1. A plurality of movable elements, restraining means normally holding said elements in normal position, controlling members for said elements, means for operating said controlling members, pawls pivotally connected to said controlling members, means for normally holding said pawls in ineffective position during the operation of the controlling members, and signal-controlled means for withdrawing said last 55 mentioned means to permit said pawls to release said restraining means from the movable elements.

2. A plurality of movable elements, restraining means normally holding said elements in normal position, controlling mem-

bers for said elements, means for operating said controlling members successively, pawls pivotally connected to said controlling members, means for normally holding said pawls in ineffective position during the operation 70 of the controlling members, and signal-controlled means for withdrawing said last mentioned means to permit said pawls to release said restraining means from the movable elements. 75

3. A receiving translator comprising a plurality of selectively operable elements, means to automatically select said elements, a contact adapted to be operated by each of said elements, and an additional contact 80 adapted to be operated by any one of said elements.

4. A receiving translator comprising a plurality of selectively operable elements, means to automatically select said elements, a contact adapted to be operated by each of said elements, a bail in the path of all of said elements, and an additional contact under the control of said bail whereby said additional contact is operated upon the operation of any one of said elements. 85

5. A receiving translator comprising a plurality of selectively operable elements, means to automatically select said elements, a contact adapted to be operated by each of said elements, a bail adapted to move upon the combined operation of certain of said elements, and an additional contact under the control of said bail. 95

6. An electrically operating translator 100 comprising a plurality of movable elements, separate restraining means for each of said elements to hold the latter in normal position, a controlling member corresponding to each of said elements, means for separately operating each of said controlling members, pawls carried by said controlling members, means normally holding said pawls out of operative relation to the corresponding restraining means, a universal bar normally retaining said pawls from the restraining means, and electrically operating means to actuate said universal bar to permit one or more of said pawls to move into coactive relation to the corresponding restraining 105 means prior to the operation of a corresponding controlling member. 110

7. An electrically operating translator comprising a plurality of movable elements, latches normally holding said elements in normal position, controlling members corresponding to said elements, each controlling member having a pawl to coact with a corresponding latch, selectively operative means normally holding said pawls out of cooperative relation to the corresponding latches, a shaft having cams to operate said controlling members separately independent 120 of said selectively operating means, means to rotate said shaft step by step, and elec- 125

trically operating means to restore all of said movable elements to normal.

8. An electrically operating translator comprising a plurality of movable elements, 5 latches normally holding said elements in normal position, controlling members corresponding to said elements, each controlling member having a pawl to coact with a corresponding latch, selectively operative means 10 normally holding said pawls out of co-operative relation to the corresponding latches, a shaft having cams to operate said controlling members separately independent of said selectively operating means, means to rotate 15 said shaft step by step, one of said pawls coactive with one of said latches being uncontrolled by said selectively operating means to cause operation of a corresponding latch and its corresponding movable element upon the 20 termination of rotation of said shaft, and means actuated by the operation of the last named movable element to cause restoration of all of said elements and their latches to the normal position.

25 9. An electrically operating translator comprising a plurality of movable elements, latches normally holding said elements in normal position, controlling members corresponding to said elements, each controlling 30 member having a pawl to coact with a corresponding latch, selectively operative means normally holding said pawls out of co-operative relation to the corresponding latches, a shaft having cams to operate said controlling members separately independent of said selectively operating means, means to rotate 35 said shaft step by step, one of said pawls coactive with one of said latches being uncontrolled by said selectively operating 40 means to cause operation of a corresponding latch and its corresponding movable element upon the termination of rotation of said shaft, a magnet, and a restoring bar operative by said magnet and adapted to 45 restore all of said movable elements to normal upon the operation of the last named movable element.

10. An electrically operating translator comprising a plurality of movable elements, 50 restraining means normally holding each of said elements in normal position, a controlling member corresponding to each of said elements, means for separately operating each of said controlling members, devices operable by said controlling members and normally out of coaction with said restraining means, a magnet, means controlled by said magnet to normally retain said devices out of coaction with the restraining means, said 55 last named means being operable by the magnet to permit any of said devices to assume an operative relation with respect to the corresponding restraining means to release the corresponding element, a magnet, 60 and a restoring bar operative by said magnet 65 and a restoring bar operative by said magnet

and adapted to restore all of said movable elements to normal upon the operation of the last named movable element.

11. A plurality of movable elements, a controlling member corresponding to each 70 of said elements, means operative by a signal on the line and in turn operative independently of any signals on the line for operating said controlling members, the operation of said controlling members being 75 normally ineffective, and signal-controlled means operative independently of the first named means to render the operation of the controlling members effective to control said movable elements. 80

12. A plurality of movable elements, a controlling member corresponding to each 85 of said elements, means operative by a signal on the line and in turn operative independently of any signals on the line for operating said controlling members successively, the operation of said controlling members being normally ineffective, and signal-controlled means operative independently of the first named means to render the 90 operation of the controlling members effective to control said movable elements.

13. A plurality of movable elements, a controlling member corresponding to each 95 of said elements, means operative by a signal on the line and in turn operative independently of any signals on the line for operating said controlling members, the operation of said controlling members being normally ineffective, signal-controlled means 100 operative independently of the first named means to render the operation of the controlling members effective to control said movable elements, and means for restoring said movable elements to normal position. 105

14. A plurality of movable elements, a controlling member corresponding to each 110 of said elements, means operative by a signal on the line and in turn operative independently of any signals on the line for operating said controlling members, and a signal-controlled device operative independently of the first named means, whereby the operation of each of the movable elements is effected only upon the conjoint operation of its corresponding controlling member and the signal-controlled device. 115

15. A plurality of movable elements, a controlling member corresponding to each 120 of said elements, means operative by a signal on the line and in turn operative independently of any signals on the line for operating said controlling members successively, a signal-controlled device operative 125 independently of the first named means, and means whereby the operation of each of the movable elements is effected only upon the conjoint operation of its corresponding controlling member and the signal-controlled device. 130

16. A plurality of movable elements, a controlling member corresponding to each of said elements, means operative by a signal on the line and in turn operative independently of any signals on the line for operating said controlling members, a signal-controlled device operative independently of the first named means, means whereby the operation of each of the movable elements is effected only upon the conjoint operation of its corresponding controlling member and the signal-controlled device, and means for restoring said movable elements to normal position.
17. A plurality of movable elements, restraining means normally holding each of said elements in normal position, a controlling member corresponding to each of said elements, means for operating said controlling members, a signal-controlled device, and means whereby the restraining means for any movable element is released therefrom only upon the conjoint operation of the corresponding controlling member and the signal-controlled device.
18. A plurality of movable elements, restraining means normally holding each of said elements in normal position, a controlling member corresponding to each of said elements, means for operating said controlling members successively, a signal-controlled device, and means whereby the restraining means for any movable element is released therefrom only upon the conjoint operation of the corresponding controlling member and the signal-controlled device.
19. A plurality of movable elements, a controlling member corresponding to each of said elements, a contact adapted to be operated by each of said elements, means operative by a signal on the line and in turn operative independently of any signals on the line for operating said controlling members, the operation of said controlling members being normally ineffective, signal-controlled means operative independently of the first named means to render the operation of the controlling members effective to cause said movable elements to operate their respective contacts and retain them operated, and means for restoring said elements to permit the restoration of said contacts.
20. An electrically operating translator comprising a plurality of movable elements, restraining means normally holding each of said elements in normal position, a controlling member corresponding to each of said elements, means for separately operating each of said controlling members, devices operable by said controlling members and normally out of coaction with said restraining
- means, a magnet, and means controlled by said magnet to normally retain said devices out of coaction with the restraining means, said last named means being operable by the magnet to permit any of said devices to assume an operative relation with respect to the corresponding restraining means to release the corresponding movable elements.
21. An electrically operating translator comprising a plurality of movable elements, separate restraining means normally holding each of said elements in normal position, a controlling member corresponding to each of said elements, each controlling member having a pawl adapted to coact with the corresponding restraining means, and electrically operating means normally retaining all of said pawls out of coöperation with said restraining means, and adapted to permit each of said pawls to coact with the corresponding restraining means upon the operation of its controlling member, and means to separately operate said controlling means.
22. An electrically operating translator comprising a plurality of selective movable elements, separate restraining means normally holding each of said elements in normal position, a controlling member corresponding to each of said elements, each controlling member having a pawl adapted to coact with the corresponding restraining means, electrically operating means normally retaining all of said pawls out of coöperation with said restraining means, and adapted to permit all of said pawls to move into operative relation to all of said restraining means, and means to operate said controlling members successively to cause the operation of the corresponding restraining means only corresponding to the selected movable element.
23. An electrically operating translator comprising a plurality of movable elements, latches normally holding said elements in normal position, controlling members corresponding to said elements, each controlling member having a pawl to coact with a corresponding latch, selectively operative means normally holding said pawls out of coöperative relation to the corresponding latches, a shaft having cams to operate said controlling members separately independent of said selectively operating means, and means to rotate said shaft step by step.
- Signed at New York city, in the county of New York, and State of New York, this 30th day of November, A. D. 1915.
